DISPLAY SIGN

William B. F. Hall, Fort Wayne, Ind.

Application March 14, 1934, Serial No. 715,392

17 Claims. (Cl. 40—130)

This invention relates to improvements in display signs and it consists of the matters hereinafter described and more particularly pointed out in the appended claims.

One of the objects of the invention is to provide a display sign of such unique character as to attract and hold the attention, thus making the sign ideal as an advertising medium.

Another object of the invention is to provide a sign of this kind capable of producing changing effects in the manner of ornamental combinations, which appear to stand still or to have movement in either direction.

A further object of the invention is to provide a sign of this character employing luminous tubing arranged on moving and stationary supports in the desired shape or form, in connection with means for controlling the passage of electrical energy thereto, whereby the said tubing produces an illusory effect that is bound to attract and hold attention so as to make a positive display of such advertising material as may be employed in connection with the sign.

Still another object of the invention is to provide a sign of this kind, which is simple in construction, is positive in operation and will remain operative for long periods of time without requiring service attention.

The above mentioned objects of the invention, as well as others, together with the many advantages thereof, will more fully appear as I proceed with my specification.

In the drawings:

Fig. 1 is a view in front elevation of a display sign embodying one form of the invention;

Fig. 2 is a vertical sectional view through the same on a somewhat enlarged scale as taken on the line 2—2 of Fig. 1; and

Fig. 3 is a detail vertical sectional view through a certain switch operating mechanism embodied in the sign as taken on the line 3—3 of Fig. 2.

Fig. 4 is a vertical detail sectional view on an enlarged scale, through a part of the device, as taken on the line 4—4 of Fig. 2.

Referring now in detail to that embodiment of the invention, illustrated in the accompanying drawings:

5 indicates an upright standard providing the main support for the sign and which is provided at the top with a horizontally disposed barrel or sleeve 6. The shape and structure of the standard are dependent of course, upon whether the sign is to be employed as a hanging one as from a sidewall of a building or a standing one as upon the roof of a building or other structure.

When the sign is to be used as a standing one, the standard is provided at its bottom end with a base 7 of such area as will insure the desired stability therefor and will permit of its being securely held in place.

8 indicates a stationary support in the form of an annular plate arranged concentric with the sleeve, in a vertical plane spaced inwardly from the front end of the sleeve 6. This stationary support, which is provided with a central opening 9 to accommodate parts associated with the sleeve 6, is in itself supported from the standard by means of a plurality of radial arms 11—11. The outer marginal part of this stationary support is offset forwardly to provide an annular band portion 12 having an edge finishing flange 13. The band portion 12 which carries a suitable surface finish, in this instance, is employed as the annular dial of a clock. At suitable points on the front face of the annular dial, 14 are numerals 14, preferably outlined by luminous tubing. Only the numerals 12, 3, 6 and 9 which indicate the quarter hours, are herein shown, it being understood of course, that the other associated numerals may also be employed if desired. The tubing of the various numerals are connected in series by the conductor 15 as best shown in Fig. 1. On the front face of the plate 8 near its center opening is a pair of spring contact fingers or brushes 16 and 17 respectively, the purpose of which will appear later.

Suitably mounted on the front end of the sleeve 6, as by means of the antifriction bearings 18, is a rotative support 19 in the form of an opaque disc. This disc which is of a diameter approximating that of the inside diameter of the annular dial 12, occupies a plane slightly forwardly of the same and is provided with an edge finishing flange 19a. The bearing 18 also acts as an endthrust bearing to prevent undue shifting of the disc longitudinally of the sleeve 6. On the rear side of the disc, near its center is formed a hub having gear teeth 20 thereon.

A motor 21 is supported from the bottom side of the sleeve 6 and this motor has a pinion 22 on its armature shaft. The pinion meshes with the gear teeth 20 so that when the motor is in operation, the disc 19 is continuously driven. Also on the rear side of said disc is fixed a ring 23 of insulation. This ring carries on its rear side, inner and outer collector rings 24 and 25 respectively with which the brushes 16 and 17 before mentioned, have a wiping engagement.

On the front side of the disc are provided inner and outer design forming, illuminable ele-

ments 26 and 27 respectively in the form of luminous tubing. This tubing, of course, is of such strength as to be able to withstand bursting under the centrifugal action of the rotation of the disc. Preferably the elements 26 and 27 are different in design or outline shape and may have different color effects. As shown herein, the inner element is generally of a five pointed design, while the outer element is generally of a four pointed design and includes arms 28 that overhang the plane of the annular dial 12.

One end of the tubing of the element 27 is connected by a conductor 29 (see Fig. 1) with the outer collector ring 25 while the other end of said tubing is connected by a conductor 29a with one end of the tubing forming the inner element 26. The other end of the tubing of said element 26 is connected by a conductor 30 with the inner collector ring 24.

Thus the collector rings and the tubing of the element 26-27 are connected together in series. The manner in which the respective rings are connected to current conductors, for illumination, will soon appear.

Suitably journaled within the sleeve 6 are outer and inner tubular arbors 31 and 32, with the latter projecting at both ends beyond the former and with the former projecting at both ends beyond the ends of the sleeve 6. On the front ends of said arbors are secured long and short members 33 and 34 which form the minute and hour hand respectively, for cooperation with the annular dial 12.

These arbors are driven in proper timed relation from their rear end as follows: On the rear end of the minute hand arbor is a gear 35. This gear meshes with a one-to-one gear 37 driven by a motor 38 whereby the arbor makes one revolution per hour. On the rear end of the outer or hour hand arbor is mounted a gear 39 which is driven from the gear 37 through suitable reduction gearing 40. Thus for every revolution of the minute hand 33, the hour hand moves through an arc of 30° which would correspond to the hour divisions on the annular dial.

The minute hand and the hour hand, are both outlined on their front side by luminous tubing 41 and 42 respectively and these tubings are connected in series with the tubing forming the numerals 12, 3, 6 and 9 on the annular dial as follows: On the inner arbor 32, in a plane between the hands 33-34 is fixed a disc of insulation 43 that carries a collector ring 44 on its rear side. The input side of the tubing 41 has a conductor 45 connected thereto and which conductor leads off from the output side of the tubing forming the numerals 3, 6, 9 and 12. This conductor is positioned axially in the arbor 32. The output side of said tubing has connected thereto a conductor 46 that extends through the disc 43 to be connected to the collector ring 44 thereon. The hour hand or outer arbor, carries at its front end a brush 47 that has a wiping engagement with the ring 44 as best shown in Fig. 4. This brush is connected to the input side of the tubing 42 on the hour hand and the output side of said tubing is grounded as at 42a and which ground may well be the arbor 31.

In Fig. 2, I have illustrated two transformers 48 and 49, the former being associated with the circuit of the tubings 26-27 on the rotatable support or disc 19 and the latter being associated with the series circuit of the tubing forming the numerals 14 on the annular dial 12 and the tubing 41-42 of the hands 33 and 34 respec-

tively. These transformers are of the type adapted to supply current of requisite character for the operation of the luminous tubes of the inertialess type. Each transformer is operatively connected to a positive conductor 50, while a suitable make and break device 51 is interposed between each transformer and a negative conductor 52.

The make and break device which best appears in Figs. 2 and 3 includes a pair of cam discs 53-53a both driven by a suitable type of electric motor 54 at the desired speed. In each disc is one or more notches 55 as appears in Fig. 3. Associated with each cam disc is a mercury tube switch 56-57 each mounted on an arm 58 pivoted at one end 59 for rocking movement. The other end of each arm carries a lug 58a which rides on the periphery of the associated cam 53-53a. Each tube switch includes a container in which are secured spaced contacts 60-61 and a quantity of mercury 62. In the rotation of the cams 53-53a, the associated arm 58 is caused to rise and fall and this will cause the mercury to move from a position in the tube which causes a making of a circuit between the contacts 60-61 to one breaking the circuit between said contacts.

Each transformer includes primary and secondary windings 68 and 63 respectively. One end of the primary winding of each transformer is connected to the conductor 50, while the other end of said winding of each transformer is connected to the conductor 52 through the associated switch 56-57 of the make and break device 51.

One end of the secondary winding 63 of the transformer 48 is connected by a conductor 64 with the brush 17 before mentioned. The other end of said winding is connected to the brush 16 by a conductor 64a. The mid point of said winding is grounded as at 65. One end of the secondary winding 63 of the transformer 49 is connected by a conductor 66 with the input side of the tubing forming the numeral 12. The other end of the secondary winding of the transformer 49 is grounded as at 67.

It is apparent that in the rotation of the disc 8 and the hands 33-34, circuits are made and broken to the various tubings in accordance with the control as afforded by the switches 56-57 of the make and break device 51. Thus there is provided a plurality of elements, capable of illumination and capable of producing real and unreal images and one of said elements is stationary or non-rotative while others are illuminated and rotated at different speeds relative to each other.

It is apparent that the periods of illumination of the various elements are intermittent and this in combination with the movement of the movable elements produces changing displays that will naturally attract attention thereto. By changing the speed of rotative disc, and by changing the "off" and "on" periods of illumination these displays or effects are likewise changed and therefore a multitude of variations in the display is possible.

While in describing the invention, I have referred in detail to the form, arrangement and construction of the various parts thereof, the same is to be considered only in the illustrative sense, so that I do not wish to be limited thereto except as may be specifically set forth in the appended claims.

I claim as my invention:

1. In a device of the kind described, the combination of a stationary support, a dial on said sta-

tionary support and having characters thereon, illuminable hands operatively associated with said dial, a second support rotatively mounted on said stationary support coaxial with said dial and hands, illuminable means on said second support and arranged as a design, means for moving said hands relative to the dial and to each other, means for rotating said second support at a speed different from that of the hands, and means for causing 5 illumination of said hands and said illuminable means at desired intervals.

2. In a device of the kind described, the combination of a stationary support, a dial on said stationary support and having illuminable characters thereon, illuminable hands operatively associated with said dial, a second support rotatively mounted on said stationary support coaxial with said dial and hands, illuminable means on said second support and arranged as a design, means 10 for moving said hands relative to the dial and to each other, means for rotating said second support at a speed different from that of the hands, and means for causing illumination of said dial characters, said hands and said illuminable means 15 at the desired intervals.

3. In a device of the kind described, the combination of a stationary support, a dial on said stationary support and having illuminable characters thereon, illuminable hands operatively associated with said dial, a second support rotatively mounted on said stationary support coaxial with said dial and hands, illuminable means on 20 said second support and arranged as a design, means for moving said hands relative to the dial and to each other, means for rotating said second support at a speed different from that of the hands, means for causing illumination of said dial characters and hands, and other means for causing 25 illumination of said illuminable means at the desired intervals.

4. In a device of the kind described, the combination of a stationary support, an annular dial on said stationary support and having illuminable characters thereon, illuminable hands operatively associated with said annular dial, a member arranged on said support for rotation axially of and within said annular dial, illuminable means mounted on said member and arranged as a design thereon, means for moving said hands relative to the dial and to each other, means for rotating said member at a speed different from that of the hands, and means for causing illumination of 30 said illuminable means on said member at the desired intervals.

5. In a device of the kind described, the combination of a stationary support, an annular dial on said stationary support and having illuminable tubing characters thereon, hands operatively associated with said dial and carrying illuminable tubing, a member arranged on said support for rotation axially of and within said annular dial, illuminable tubing on said member arranged as a design, means for moving said hands relative to the dial and to each other, means for rotating said member at a speed different from that of the hands, means for causing the illumination of the tubing on the dial and hands respectively at the desired intervals, and means for causing the illumination of the tubing on said member at desired intervals during the rotation of said member.

6. In a device of the kind described, the combination of an annular dial having illuminable characters thereon, illuminable hands operatively associated with the dial, a support arranged

axially of the dial for rotation, illuminable tubings, arranged in a plurality of different formations on the support and connected in series, means for moving the hands relative to the dial and to each other, means for rotating the support, means for illuminating the hands, and means for causing illumination of the tubings on the support at the desired intervals during its rotation.

7. In a device of the kind described, a support including a bearing member, means providing an annular dial on said support and having characters thereon, arbors journalled in said bearing member, illuminable hands, one secured to each arbor, a second support rotatably mounted on the bearing member, illuminable tubing carried on said second support, means for driving said arbors in timed relation so that said hands move with respect to the dial and to each other, means for driving said second support, means for illuminating said hands, and means for causing illumination of said tubing on said second support at the desired intervals during the rotation thereof.

8. In a device of the kind described, a support including a bearing member, means providing an annular dial on said support and having characters thereon, arbors journalled in said bearing member, illuminable hands, one secured to each arbor, a second support rotatably mounted on the bearing member and provided with an annular toothed portion, a motor on said support, means driven by said motor and operatively connected to said toothed portion so as to drive said second support, illuminable tubing carried by said second support, means for driving said arbors in timed relation so that said hands move with respect to the dial and to each other, means for illuminating said hands, and means for causing illumination of the tubing on said second support at the desired intervals during the rotation thereof.

9. In a device of the kind described, the combination of an annular dial member having illuminable characters thereon, illuminable hands operatively associated with said dial member, a support arranged axially of the dial for rotation, illuminable tubing on said support, means for moving the hands relative to said dial and to each other, means for rotating the support, series circuit for said illuminable characters and hands, means for making and breaking said circuit at the desired timed intervals, a second circuit for said tubing on said support, and other means for making and breaking said second circuit.

10. In a device of the kind described, means providing an annular dial member having characters thereon, a rotatable supporting member arranged axially with respect to said dial member and having a plurality of illuminable tubings thereon arranged in different outline forms to 50 coact in producing a composite figuration, a plurality of illuminable hands mounted coaxially with said support and dial member, means for moving the hands with respect to the dial and to each other, and means for controlling the periods 55 of illumination of said hands and said plurality of illuminable tubings on said support.

11. In a dial of the kind described, the combination of a dial with characters thereon and associated rotatably mounted illuminable hands, a member mounted for rotation coaxial with said dial and hands, illuminable means arranged in the desired design on said member with portions overlapping said dial, means for moving the hands relative to the dial and to each other, means for 75

rotating said member at a speed different from that of the hands, and means for causing illumination of said illuminable hands and said illuminable means respectively at the desired intervals.

5. 12. In a device of the kind described, the combination of a dial with characters thereon and associated rotatably mounted illuminable hands, a member mounted for rotation coaxial with said dial and hands, illuminable means arranged as

10 a plurality of designs, one of which has portions disposed in operative relation with respect to the dial, means for moving the hands relative to the dial and to each other, means for rotating said member at a speed different from that of the hands, and means for causing illumination of said illuminable hands and said illuminable means respectively at the desired intervals.

15. 13. In a device of the kind described, the combination of a dial with characters thereon and associated rotatably mounted illuminable hands, a member mounted for rotation coaxial with said dial and hands, illuminable means arranged as inner and outer designs with parts of the latter overlapping the dial, means for moving the hands relative to the dial and to each other, means for rotating said member at a speed faster than that of the said hands, and means for causing illumination of said illuminable hands and said illuminable means respectively at the desired intervals.

20. 14. In a device of the kind described, the combination of an annular dial having illuminable characters thereon, illuminable hands operatively associated with the dial, a support arranged axially of the dial for rotation, illuminable tubing on said support and arranged in a geometrical design with a portion overlapping a part of the dial, means for moving the hands relative to the dial and to each other, means for rotating the support, means for illuminating the hands, and means for causing illumination of the tubing on the support at the desired intervals during the rotation of said support.

25. 15. In a device of the kind described, the combination of an annular dial having illuminable characters thereon, illuminable hands operatively associated with and spaced forwardly of said dial, a support arranged axially of the dial for rotation,

illuminable tubing carried by said support and arranged in a plane between said hands and dial respectively and having a portion arranged to overlap a part of the latter, means for moving the hands relative to the dial and to each other, means for rotating the support, means for illuminating the hands, and means for causing illumination of the tubings on the support at the desired intervals during its rotation.

30. 16. In a device of the kind described, the combination of a stationary member formed to provide an annular dial having illuminable characters thereon, illuminable hands operatively associated with the dial, a support arranged axially of the dial for rotation, an illuminable tubing formation on said support, means providing a brush and collector ring mechanism on said member and rotatable support respectively and to which the illuminable tubing on the rotatable support is electrically connected, electric circuits, one for said illuminable characters and hands respectively and one for said brush and collector ring mechanism, a transformer in the circuit for said brush and collector ring mechanism, a switch mechanism for controlling the off and on periods for both circuit, means for moving the hands, and means for rotating said support at a speed different from that of said hands.

35. 17. In a device of the kind described, the combination of a stationary member formed to provide an annular dial with characters thereon outlined by illuminable tubing, hands operatively associated with said dial and also outlined by illuminable tubing, a support arranged axially of the dial for rotation, an illuminable tubing formation on said support, means providing a brush and collector mechanism on said member and rotatable support respectively and to which the illuminable tubing on said support is electrically connected, electric circuits, one for the tubing of said characters and hands respectively and one for said brush and collector ring mechanism, a transformer in each circuit, a switch mechanism for controlling the "off" and "on" period for both circuits, and means for moving the hands and for rotating the support at a speed different from that of said hands.

WILLIAM B. F. HALL.
